UNITED STATES PATENT OFFICE.

ANTON W. JOHANSON, OF CHICAGO, ILLINOIS.

DESIGN FOR A HANDLE OF A SPOON OR SIMILAR ARTICLE.

49,355.

Specification for Design.

Patented July 11, 1916.

Application filed April 20, 1916. Serial No. 92,554. Term of patent 7 years.

To all whom it may concern:

Be it known that I, ANTON W. JOHANSON, a citizen of the United States, and a resident of the city of Chicago, county of Cook, and State of Illinois, have invented a new, original, and ornamental Design for the Handle of a Spoon or Similar Article, of which the following is a specification, reference being had to the accompanying drawings, forming a part thereof.

The figure is a plan view of a spoon showing my new design.

Copies of this patent may be obtained for five cents each, by addressing the "Commissioner of Patents, Washington, D. C."

I claim:

The ornamental design for the handle of a spoon or similar article, as shown.

In testimony whereof I have signed my name to this specification in the presence of two subscribing witnesses.

ANTON W. JOHANSON.
